Dec. 1552

Clemir J. Ney, of Lowell, Mass.
Assignor to
The Lowell Manufacturing Co. of same place.
Letters Patent No. 1552, dated March 18, 1862.

The schedule referred to in these Letters Patent and making part of the same.

To all whom it may concern:

Be it known that I, Clemir J. Ney, of Lowell, in the County of Middlesex and State of Massachusetts, have originated and designed a new Pattern for Carpets or other fabrics, of which the following is a full, clear and exact description, reference being had to the accompanying drawing, making part of this specification.

Corners 1. 2. 3. 4, when matched from a stem with rose bud and leaves attached do.

A, in the centre is a group of flowers and leaves.
Four small leaves 5. 5. 5. 5. lie at equal distances between the centre and corners.

Figs. 6. 6. are small acorns.

All of the figures before mentioned rest on a ground of coral work.

The colors employed for the different portions of the design, may be varied to suit the taste and wish of the manufacturer.

Claim.

What I claim as my invention and desire to secure by Letters Patent, is the design or pattern for Carpets or other fabrics, herein set forth.
